UNITED STATES PATENT OFFICE.

CHARLES L. RAYFIELD, OF CHICAGO, ILLINOIS, ASSIGNOR TO BENEKE MANUFACTURING COMPANY, OF CHICAGO, ILLINOIS, A CORPORATION OF ILLINOIS.

CARBURETOR.

Application filed April 2, 1923. Serial No. 629,334.

To all whom it may concern:

Be it known that I, CHARLES L. RAYFIELD, a citizen of the United States, and a resident of the city of Chicago, in the county of Cook and State of Illinois, have invented certain new and useful Improvements in a Carburetor; and I do hereby declare that the following is a full, clear, and exact description of the same, reference being had to the accompanying drawings, and to the numerals of reference marked thereon, which form a part of this specification.

This invention relates to improvements incorporated in an interconnected air valve and pumping dash pot type of carburetor and comprises an auxiliary fuel nozzle and an additional accelerating nozzle adapted for rapid injection of fuel at the start of the air valve movement and prior to the opening of the auxiliary fuel nozzle by a further movement of the air valve.

It is well known that under sudden acceleration demands, especially in wet or foggy mixtures, such as are found in carburetors and intake manifolds handling the present day fuel made up of various fractional distillation products blended to form a so-called gasoline, that the sudden acceleration causes a momentary starving of the mixture due to the inertia of the globules of fuel carried by the air stream or flowing along the walls of the manifold, which do not accelerate at the same rate as the air stream. A wet mixture is admittedly as efficient as a dry one for a constant speed and load as the temperatures within the cylinder insure vaporization, but for widely variable loads and speeds as found in automotive vehicles the wet mixture gives serious distribution and acceleration problems. In an endeavor to obtain a dry mixture, preheating of the air supply and various kinds of hot spots are in use, resulting in varying degrees of loss of volumetric efficiency due to the smaller weight of air charged at a higher temperature. Heretofore various acceleration wells and the like have been proposed and it is an object of this invention to provide a novel form of preliminary injection nozzle that will practically anticipate the acceleration requirements by giving a momentarily rich mixture sufficiently in advance of the requirements therefor so that a proper mixture will reach the cylinders during the time a lag of the regular fuel supply occurs during acceleration.

It is an object of this invention to provide a positive injection of fuel into an air stream entering a carburetor, the orifices through which injection occurs being unaffected by any suction existing within the carburetor, so that no after flow can occur after cessation of movement of the injecting mechanism.

It is a further object of this invention to provide a fuel injecting mechanism operating prior to the opening of a normally partially closed air valve, and having a positive cut-off acting after a predetermined movement of the air valve.

Other and further important objects of this invention will be apparent from the disclosures in the specification and the accompanying drawings.

The invention (in a preferred form) is illustrated in the drawings and hereinafter more fully described.

On the drawings:

Figure 1 is a sectional elevation of a carburetor embodying the features of this invention, with parts in elevation.

Figure 2 is an enlarged fragmentary section on the line 2-2 of Figure 1.

As shown on the drawings:

The device of this invention is shown incorporated in a carburetor comprising a body member 1 having a flange 2 for attachment to the intake manifold or cylinder block of an internal combustion engine. A throttle valve 3 and compound nozzles 4 are indicated but not detailed as they are both well known in the prior art. A form of control valve for regulating the flow of fluid from an air inlet chamber 5 is outlined in the figure and comprises a butterfly valve 6 having a linkage connection 7 to a sleeve air valve 8 whereby when the butterfly valve 6 is open the sleeve is open and vice versa, the linkage being interconnected by a linkage 9 to the auxiliary air valve to be described hereinafter to cause opening of the valves 6 and 8 when the auxiliary air valve opens.

A dash pot chamber 10 is illustrated as disposed below and separated from the air inlet chamber 5 by a partition 11, a fuel passage 12 opening into the dash pot chamber just below the partition and leading from a fuel well 13 in connection with the compound nozzles 4. Formed integral with the partition 11 is a long upwardly extending apertured boss 14, and slidably mounted therein is a tubular stem 15 closed

at the upper end and having a conical air inlet valve 16 secured therein of slightly lesser outside diameter than the passage through an annular air inlet 17 secured in the top of the air inlet chamber 5. A spring 16a wound about the boss 14 serves to normally hold the air valve in its upper position. A boss 18 coaxial with the boss 14 and extending downwardly from the partition 11 is counterbored to a larger diameter than the stem 15 and has a bushing 19 inserted therein of an inner diameter fitting the stem 15, the bushing being of less length than the depth of the counterbore to leave an annular chamber 20 surrounding the stem 15. Of course, this chamber 20 could be formed in many other ways than by counterboring and inserting a bushing, but practically the above-outlined method is better from a commercial production standpoint, because the length of the chamber 20 can be varied by a substitution of a different length of bushing 19. Secured on the lower end of the tubular stem 15 is a flat disc 21, and loosely mounted therebeneath is a dash pot piston 22 retained in place by a suitable plate 23 carrying lugs 24 spaced from the piston 22 as to make the disc 21 a check valve allowing passage of fuel upward on an upward movement of the stem and piston, while upon a downward movement the disc presses closely upon the piston, sealing the piston against leakage.

Secured to the partition 11 is an auxiliary fuel nozzle 25 projecting upwardly to a point just below the conical air valve 16, the nozzle having a metering pin 26 and lower sliding sleeve 27 contacting the disc 21 above aligned apertures 28 through the disc and piston. This fuel nozzle is disclosed and claimed in my Patent No. 1,335,390, issued March 30th, 1920.

An adjusting screw 29 is inserted through the conical air valve 16 in line with the metering pin 26 and with the air valve in a fully closed position this set screw does not contact the head of the metering pin so that a preliminary downward movement of the air valve is necessary before the metering pin starts to open. Adjustment of the set screw 29 serves to form the high speed mixture adjustment of the carburetor as a whole. This lag in the opening of the auxiliary nozzle is essential to permit adjustment thereof and because the nozzle is under suction and when open delivers fuel to the air stream at all times rather than only during moments of sudden acceleration when the air valve opens suddenly, and consequently the nozzle would create an over-rich mixture at speeds slightly above idling if the air valve opened the nozzle during its first slight movement.

The improvements of the present invention comprise the tubular stem 15 which

communicates with a plurality of horizontal orifices 30 above the conical air valve 16. The tubular stem is plugged, as shown at 31, at a position intermediate the limits of the chamber 20 formed by the counterbore 70 and bushing 19, and a plurality of ports 32 are cut or drilled in the stem immediately above and below the plug 31 so that with the stem as shown a passage for fluid from below the piston exists up the tubular stem to the plug 31 out the lower ports into the chamber 20 and into the tubular stem through the ports above the plug, and thence out the orifices 30 above the air valve 16. With the various parts in their uppermost or idling position, as shown in the drawing, the bottom of the boss 18 serves as a stop for the disc 21 and thus determines the no-load position of the air valve which is preferably slightly above the bottom of the member 17 forming the air passage.

It will be apparent that under no operating conditions will a suction exist on the orifices 30, as is the case with the auxiliary nozzle 25 within the body of the carburetor, and that therefore only a pumping action within the dashpot will lift and eject fuel from the orifices 30. This pumping action is brought about by a downward movement of the air valve, stem and piston in response to an opening movement of the regular carburetor throttle 3, and it will be evident that the upper edge of the bushing 19 serves as a cut-off by covering the lower ports 31 in the stem 15 and thus preventing further flow of fuel through the stem. As hereinbefore mentioned, the time of this cut-off can be varied by a substitution of a bushing of a different length.

The operation of a carburetor equipped with the device of this invention is as follows: Normally under idling conditions the auxiliary air valve and fuel nozzle are in an inoperative position, as shown in the figure. Increasing demands on the carburetor due to opening the throttle will increase the depression or suction within the air chamber 5 and cause the auxiliary air valve to move downwardly because the upper surface thereof is subject to substantially atmospheric pressure. A very slight downward movement of the valve 16, stem 15 and disc 21 is sufficient to seal the latter to the piston 22 and cause a pumping action thereof that carries fuel up the tubular stem, around the plug 31, as previously described, and to spray the fuel through the orifices 30 above the air valve. With the relative proportions of stem and piston shown, a movement of the air valve of one thirty-second of an inch is sufficient to cause a spray of fuel from the orifice and this spray will continue until the top edge of the bushing 19 cuts off the lower series of ports 31 on continued downward

movement of the air valve and stem. It will be noted that the bulk of the fuel ejected from the orifices 30 is discharged prior to the time that the largest diameter of the air valve clears the bottom of the air inlet passage 17, and that therefore this injection serves to give a momentary richness prior to the admission of any extra amount of air through the valve, thus accomplishing an object of this invention by forestalling the momentary leanness of mixture caused by a sudden opening of the throttle, i. e., demands due to sudden acceleration. If the acceleration is continued, the auxiliary nozzle 25 supplies the necessary extra fuel either by forced ejection due to movement of the dash pot piston or by suction after the air valve and dash pot have reached a position of equilibrium with the suction on the valve augmented by the spring pressure balancing the external air pressure and the velocity pressure on the conical air valve.

I am aware that numerous details of construction may be varied through a wide range without departing from the principles of this invention, and I therefore do not purpose limiting the patent granted otherwise than necessitated by the prior art.

I claim as my invention:

1. In a carburetor, an air valve, a dash pot, a piston in said dash pot, a tubular connection between said air valve and said dash pot piston having orifices therein above the main portion of said

air valve, and means in and surrounding said tubular connection adapted to close the passage between said dash pot and said orifices after a predetermined movement of said connection. 35

2. In a carburetor including a fuel supply 40 means, a mixing chamber, and an automatic air valve admitting air thereto, a fuel pump mechanism connected with the air valve, and a sliding double tube fuel valve member associated with the pump mechanism. 45

3. In a carburetor including a fuel supply means, a mixing chamber and an automatic air valve, a pump mechanism, a tubular connection forming a fuel passage between said pump and air valve, said tubular 50 connection comprising means whereby the pump is adapted to be actuated by a downward movement of the air valve, and a sleeve valve associated with said connection and controlling the fuel passage. 55

4. In a carburetor, an interconnected automatic air valve and a fuel pumping dashpot, means for conducting fuel from said dashpot to outlets on the upper side of said air valve, and a sleeve valve associated 60 therewith constructed to enable the fuel conducting means to discharge fuel above said air valve only upon initial downward movement.

In testimony whereof I have hereunto 65 subscribed my name.

CHARLES L. RAYFIELD.
